Primary Examiner — Cary M Robinson*Assistant Examiner* — Adam C Mager*(74) Attorney, Agent, or Firm* — Theodore S. Lee, Esq.(57) **CLAIM**

The ornamental design for an automobile bumper, as shown and described.

DESCRIPTION

FIG. 1 is a perspective view of an automobile bumper according to the novel design;

FIG. 2 is front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.
